(57) CLAIM

I claim the ornamental design for a case for a tablet, as shown and described.

DESCRIPTION

FIG. 1 is a front perspective view of a case for a tablet; FIG. 2 is a back perspective view of the case for a tablet shown in FIG. 1; FIG. 3 is a front view of the case for a tablet shown in FIG. 1;

FIG. 4 is a back view of the case for a tablet shown in FIG. 1;

FIG. 5 is a left side view of the case for a tablet shown in FIG. 1;

FIG. 6 is a right side view of the case for a tablet shown in FIG. 1;

FIG. 7 is a top view of the case for a tablet shown in FIG. 1; and,

FIG. 8 is a bottom view of the case for a tablet shown in FIG. 1.

The broken lines illustrate environmental structures, features or boundaries that form no part of the claim.

1 Claim, 6 Drawing Sheets
